2,553,390

BUCKLE

Hector J. Streyckmans, Bronx, N. Y., assignor to
Leo C. Krazinski, New York, N. Y.

Application August 21, 1946, Serial No. 691,998

4 Claims. (Cl. 24—68)

1

My invention relates to buckles and refers particularly to buckles adapted for use in tourniquets.

In the use of tourniquets for the purpose of the stoppage of an abnormal flow of blood, it is necessary that such devices should be so constructed that they may be instantly applied and operated by the injured party and without the assistance of others and without the expert assistance of nurses or doctors.

Further, tourniquets should be small, light and readily washed and sterilized.

Further, tourniquets should be of such construction that any desired pressure can be readily obtained to completely stop the flow of blood, and as easily operated to allow the flow of blood to cleanse the wound.

It is evident, therefore, that a tourniquet should be easily and effectively operated by the wounded person without the dangerous and perhaps fatal results that would follow any delay in the proper prevention of the flow of blood coupled with the possibility of cleansing of the wound.

A consideration of my specification and its accompanying drawings will indicate the value and effectiveness of the devices of my invention for the purposes described.

While I have specifically described the buckles of my invention as applied to tourniquets, it is evident that they have other uses as buckles, and hence, I do not limit myself to the particular described uses.

In the accompanying drawings illustrating one form of a device of my invention similar parts of my invention are designated by similar numerals.

Figure 1 is a side view of one form of my invention with the belt in fixed position and with the desired pressure upon an arm.

Figure 2 is a top view of the device of Figure 1 with the belt omitted.

Figure 3 is a section through the line 3—3 of Figure 2.

Figure 4 is a section through the line 4—4 of Figure 2.

Figure 5 is a top perspective view of the device of Figure 1 with the belt removed.

Figure 6 is a perspective view of the binding member.

Figure 7 is a fragmentary sectional view of the device of Figure 1, with the belt in fixed position prior to the application of the desired pressure.

The particular form of a device of my invention shown in the accompanying drawings comprises a plate having the base member 10 and the angularly positioned end member 11, the base

2

member having the two cut-outs 12, 12 and the end member 11 having a slot 13 and an opening 14 with the inwardly extended cylindrical internally threaded boss 15. The base member 10 has the slot 16 and the slot 17.

A U-shaped binding member 20 has four extended arms 21, 21, 21, 21 having aligned openings 22, 22 therethrough. The upper portion of the binding member 20 has an upturned edge 23 and the lower portion of the binding member 20 has a downwardly extended edge 24. A stop rivet member 25 passes downwardly through each pair of aligned openings 22, 22.

A setting device comprises the threaded cylindrical member 30, adapted to mesh with the threads of the boss 15, the outer end of the member 30 having the fixedly attached finger piece 31, and the inner end of the member 30 having the fixedly attached belt stretching member 32.

When the device is assembled, the binding member 20 is slidable over the inner portion of the base member 10, its complete removal therefrom being prevented by the abutment of the stop rivets, 25, 25 against the outer shoulder of the cut-outs 12, 12.

A belt 40 is passed inwardly through slot 13, thence fastened to prevent its complete passage therethrough, thence over the belt stretcher 32, thence downwardly through the base member slot 16, looped and passed upwardly through the slot 17 and thence downwardly through the space between the inner edge of the base member 10 and the inner portion of the binding member 20 with the binding member in its outer position.

In operation the arm 50 or other member upon which the device is to be applied, is placed through the looped portion of the belt 40 and the free end of the belt is pulled outwardly until the belt is firmly placed around the arm, as shown in Figure 7.

The binding member 20 is then moved inwardly until its edges 23 and 24 are firmly abutted upon the belt 40, thus preventing the belt from movement in either direction.

The setting member 30 is then revolved moving the belt stretching member 32 inwardly against the belt 40 thus shortening the loop and causing it to press upon the arm to any required pressure, as shown in Figure 1.

To remove the device the free end of the belt 40 is drawn outwardly thus causing the binding member 20 to slide outwardly and removing it from abutment against the belt and thus allowing of free movement of the belt through the device.

It is evident that instead of passing an arm through the belt loop as previously mentioned, the strap may be unthreaded from the device and the belt may be threaded around the arm, thus allowing the device to be employed in the 5 most convenient manner.

It will be noted that my device can be readily and rapidly placed around the member upon which it is to be operated, and that by a few turns of the setting member 30, any desired 10 pressure may be obtained and released.

Before medical aid can be obtained, it is frequently imperative that the rapid escape of blood be slowed or stopped by means of a tourniquet applied to the body in the proximity of the 15 wound, and that repressive pressure be applied.

In the absence of a properly constructed tourniquet, this is usually faultily accomplished by 20 passing a band around the member and twisting the band by means of stick of metal or wood, which twisted position must be manually maintained until proper medical treatment can be obtained; and if this is performed by the wounded person, he frequently becomes so weak that he is unable to maintain the required pressure 25 and he bleeds to death.

Further, in order to cleanse the wound and to prevent it from sealing too quickly, the blood must be allowed to flow through the wound intermittent of the blood stoppages, a performance which the injured person is scarcely ever able to accomplish.

My device overcomes all of the above and other dangerous possibilities incident to the employment of makeshift devices.

My device is small and light in weight and may be readily introduced into a doctor's bag or a serviceman's kit. It is easily and quickly applied by the wounded person who can accurately and readily apply any desired pressure, and release it by a few turns of the setting device and it does not require attention to maintain the desired pressure.

For war service use it may be so constructed that the man's usual belt can be inserted for use, thus obviating the necessity of a separate belt.

It is evident, therefore, that the devices of my invention have high values for both service and civilian use.

I do not limit myself to the particular size, shape, number, arrangement and materials mentioned and described as these may be varied without going beyond the scope of my invention.

What I claim:

1. A buckle comprising a base member having an upwardly extended member, said base member having a pair of parallel slots therein and aligned cut-out side portions, and said upwardly extended member having a slot therein and a threaded annular opening below said last mentioned slot; an annular threaded member passing through said annular threaded opening and meshing therewith; an elongated belt stretching member fixedly attached to the inner end of said annular threaded member; a U-shaped binding member slidable over the inner end portion of said base member, each side portion of said binding member having an outwardly extended arm having an opening therein, and means passing through said arm openings and within the 55 cut-outs of said base member adapted to limit

the movement of said binding member over said base member.

2. A buckle comprising a base member having an upwardly extended member, said base member having a pair of parallel slots therein and aligned cut-out side portions, and said upwardly extended member having a slot therein and a threaded annular opening below said last mentioned slot; an annular threaded member passing through said annular threaded opening and meshing therewith; an elongated belt stretching member fixedly attached to the inner end of said annular threaded member; a binding member slidable over the inner end portion of said base member, and stop means on said binding member disposed in said cut-out side portions adapted to limit the extent of movement of said binding member.

3. A buckle comprising a base member having an upwardly extended member, said base member having a pair of parallel slots therein and aligned cut-out side portions, and said upwardly extended member having a slot therein and a threaded annular opening below said last mentioned slot; an annular threaded member passing through said annular threaded opening and meshing therewith; an elongated belt stretching member fixedly attached to the inner end of said annular threaded member; a U-shaped binding member slidable over the inner end portion of said base member and stop means on said binding member disposed in said cut-out side portions adapted to limit the extent of movement of said binding member.

4. A buckle comprising a base member having an upwardly extended member, said base member having a pair of parallel slots therein and aligned cut-out side portions, and said upwardly extended member having a slot therein and a threaded annular opening below said last mentioned slot; an annular threaded member passing through said annular threaded opening and meshing therewith; an elongated belt stretching member fixedly attached to the inner end of said annular threaded member; a U-shaped binding member slidable over the inner end portion of said base member, each side portion of said binding member having an outwardly extended arm, and stop means on each of said arms disposed in said cut-out side portions adapted to limit the extent of movement of said binding member.
